DESIGN FOR A WAFFLE IRON OR SIMILAR ARTICLE

Joseph E. Barrett, Cape Girardeau, Mo., assignor to Superior Electric Products Corp., Cape Girardeau, Mo., a corporation of Missouri

Application December 7, 1938, Serial No. 31,618

Term of patent 3½ years

To all whom it may concern:

Be it known that I, Joseph E. Barrett, a citizen of the United States, residing in the city of Cape Girardeau, county of Cape Girardeau, and State of Missouri, have invented a new, original, and ornamental Design for a Waffle Iron or Similar Article, of which the following is a specification, reference being had to the accompanying drawing, forming a part thereof.

In the drawing:

Fig. 1 is a top plan view of a waffle iron or similar article, showing my design; and

Fig. 2 is a front elevational view thereof.

The dominant feature of the design resides in the base portion of the waffle iron or similar article, shown in full lines.

I claim:

The ornamental design for a waffle iron or similar article, substantially as shown and described.

JOSEPH E. BARRETT.
